UNITED STATES PATENT OFFICE

SAMUEL A. NEIDICH, OF EDGEWATER PARK, NEW JERSEY

METHOD OF ETCHING CELLULOID AND THE LIKE

Application filed March 13, 1929. Serial No. 346,787.

My invention relates to means for etching products of cellulose, such as celluloid, cellulose nitrate, cellulose acetate, and similar materials, to afford recesses for the reception of other material which may be of an ornamental character or be printers' ink or other pigment which may be transferred from such etching.

As hereinafter described, my invention includes the method of applying to the surface to be etched, a fluid which is a solvent of the material to be etched and capable of penetrating that surface and increasing the volume of the material penetrated; thus producing cameo projection of the material at the region penetrated; removing the projecting material; and removing the remaining fluid from said region penetrated, and thus causing intaglio recession of that region.

I prefer to use, for the penetrating fluid aforesaid, a cellulose nitrate solvent having a high boiling point and low volatility; and particularly derivatives of ethylene glycol and diethylene glycol; for instance, ethylene glycol mono ethyl ether acetate, diethylene glycol mono butyl ether, etc.

As a matter of economy and control of the solvents aforesaid, they may be mixed with diluents. For instance, ethylene glycol mono ethyl ether acetate and similar derivatives of ethylene glycol may be diluted with water. However, I prefer to employ a more volatile diluent, such as carbon tetrachloride or liquid hydrocarbons. For instance, such a solvent may include ethylene glycol mono ethyl ether, mixed with such a volatile diluent as carbon tetrachloride, gasoline or naphtha. Altho gasoline and naphtha may be used in lieu of carbon tetrachloride as diluents of cellulose nitrate solvents; carbon tetrachloride is preferable because it is not inflammable like the hydrocarbons aforesaid.

For example, the etching fluid may be composed of twenty percent of ethylene glycol mono ethyl ether acetate, or other derivative of ethylene glycol, mixed with eighty percent of carbon tetrachloride. The etching fluid may be applied to the surface to be etched by any convenient method or means.

My invention includes the various novel

features of procedure, composition and structure hereinafter more definitely specified.

In said drawings; Fig. I is an edge view of a sheet of such cellulose product having certain regions of its upper surface exposed for access of the etching fluid; the other portions being masked.

Fig. II is a view similar to Fig. I, but showing the effect of the etching fluid upon the exposed areas of the celluloid or the like.

Fig. III is a view similar to Fig. II, but with the masking material removed and with the cameo projections of the celluloid and the like removed, leaving the top surface substantially flush.

Fig. IV is a view similar to Fig. III but with the penetrating fluid removed from the regions penetrated, causing intaglio recession of those regions.

Fig. V is a perspective view of a tube of celluloid or the like, having a coating of masking material, removed by writing thereon.

Referring to Fig. I; the sheet 1 of celluloid or the like cellulose product has regions 2 thereof exposed for subjection to the action of the etching fluid; the other regions thereof being covered by the coating of masking material 3 which may be paraffin or any other etching resistant material which may be readily removed from the celluloid product.

Referring to Fig. II; the etching fluid 5 may be conveniently applied by spraying it thru the air brush nozzle 6 with the effect of penetrating the subjacent region 2 of the sheet 1 and increasing the volume of the material treated so that it projects as indicated at 8. After the exposed areas 2 have been thus treated; the masking material may be removed in any convenient manner, for instance, by warming the sheet 1. Thereupon, the cameo projections 8 upon the sheet 1 may be removed, conveniently by grinding them with an abrading wheel 10, as indicated in Fig. III.

Thereafter, the remaining penetrating fluid in the regions 2 of the sheet 1 may be removed, either by spontaneous evaporation of said fluid, or by extracting said fluid in a

diluent thereof, for instance, by bathing said sheet with carbon tetrachloride. The effect of the removal of the residual penetrating fluid from the regions 2 is to cause intaglio recession of those regions, as indicated at 12 in Fig. IV, leaving the sheet 1 with the appearance of having been engraved.

The etched sheet 1 aforesaid may then have the recessed regions 12 thereof filled 10 with a cellulose product of contrasting texture or color or with other material, such as a paint pigment or ink.

As above noted, the recessed regions 12 of such an etched plate 1 may be temporarily charged with engraving ink and said sheet 15 used as a printing element to transfer such ink to a sheet of paper or other suitable fabric.

The masking material 3 may be applied in 20 any convenient manner by any suitable means; for instance, such material as liquid paraffin or other waxy substance may be sprayed upon the sheet 1 thru a perforated pattern which temporarily covers the regions 25 2 of said sheet which are to be exposed and which are uncovered when the pattern is removed. However, the article to be etched may have the surface thereof which it is intended to etch initially entirely covered with 30 the masking material, which is thereafter removed, thruout the regions to be etched, by any suitable method or means. For instance, referring to Fig. V, the tube 14 of celluloid or the like, which may be a fountain pen body 35 or cap, or a handle covering for a cane or umbrella, may be primarily masked by a coating 15 of suitable material, for instance, paraffin, which may then be removed thruout the region 16 to be etched, by writing thereon 40 with an ordinary lead pencil, or other etching implement. The tube shown in Fig. V may have the exposed surface 16 thereof subjected to the action of a penetrating fluid with the effect of causing the material of the 45 tube to project, as at 8 in Fig. II, and said tube may be subsequently treated as above contemplated to effect recession of the region 16.

Therefore, I do not desire to limit myself 50 to the precise details of construction and arrangement herein set forth, as it is obvious that various modifications may be made therein without departing from the essential features of my invention as defined in the 55 appended claims.

1 claim:

1. The method of etching celluloid and the like, which includes applying to the surface to be etched, a fluid which is a solvent of the 60 material to be etched and capable of penetrating that surface and increasing the volume of the material penetrated; thus producing cameo projection of the material at the region penetrated; removing the projecting 65 material; and removing the remaining fluid

from said region penetrated, and thus causing intaglio recession of that region.

2. A method as in claim 1; wherein the fluid includes ethylene glycol mono ethyl ether acetate.

3. A method as in claim 1; wherein the fluid includes ethylene glycol mono ethyl ether, mixed with a fluid diluent.

4. A method as in claim 1; wherein the fluid includes ethylene glycol mono ethyl ether, mixed with carbon tetrachloride.

In testimony whereof, I have hereunto signed my name at Burlington, New Jersey, this 31st day of January, 1929.
